ATTORNEY

UNITED STATES PATENT OFFICE.

CHARLES C. MILLER, OF FORT WAYNE, INDIANA.

FOLDING BOX.

1,421,526.

Specification of Letters Patent. Patented July 4, 1922.

Application filed April 16, 1921. Serial No. 462,002.

To all whom it may concern:

Be it known that I, CHARLES C. MILLER, a citizen of the United States, residing at Fort Wayne, in the county of Allen and State of Indiana, have invented new and useful Improvements in Folding Boxes, of which the following is a specification.

The invention relates to boxes and particularly to knock-down boxes adapted for use in laundries, mercantile establishments and the like for the packing of articles to be delivered or transported.

The object of the invention is to provide a simple and cheap box with cover, formed out of a single sheet of material and occupying a minimum of space in knock-down form, the box being readily and very quickly set up for use.

The invention consists in a box having an integral cover, the side walls of both the cover and body of the box being collapsible, and the side walls of the body being adapted to be maintained in substantial upright position by frictional means.

In the accompanying drawings the invention is illustrated in simple form, in which—

Figure 1 is a plan view of a blank for the box; Fig. 2 a plan view of the same with the end flaps of the body folded over on the bottom of said body, the lateral wings of said end flaps being secured to the side walls of the body; Fig. 3 a perspective view of the box prior to being set up; Fig. 4 a plan view of the box set up for the deposit of articles therein; Fig. 5 a perspective view of the box in closed condition; Fig. 6 a cross-sectional view on line 6—6 of Fig. 4; Fig. 7 a cross-sectional view on line 7—7 of Fig. 6, and Fig. 8 a cross-sectional view illustrating a modification of the locking flap.

Referring to the drawings, the blank indicated generally by reference character 10 is formed or stamped out of a single sheet of material such as paper board of suitable weight. At the same time that the blank is cut out it is also scored both longitudinally and transversely as shown in Fig. 1, by the broken lines. Scoring 11 forms a side flap 12 on the top 13 of the cover; scorings 14 and 15 form side flap 16 constituting a common side of the cover and of the body of the box and scoring 17 forms side flap 18 constituting the other side of the body of the box. Scoring 19 forms end flap 20 of the cover, scoring 21 forms the opposite end flap 22 of the cover, scoring 23 forms an end

flap 24 of the body of the box and scoring 25 forms the opposite end flap 26 of the body of the box. Wings 27 and 28 are formed at opposite ends of end flap 24, wing 27 being formed by cutting through the material on the solid lines 29, 30 and 31 and by scoring 32, and wing 28 being formed by cutting through the material on solid line 33 and by scoring 34. A series of indentations 35 is formed in each wing adjacent and parallel to its oblique edge to form on each wing a flap 36. Wings 37 and 38 having flaps 39 are similarly formed at the opposite end of the blank. The wings and flaps thereon form hinges at opposite ends of the end flaps 24 and 26. The section of the material bounded by scorings 15, 23, 17 and 25 forms the bottom 46 of the body of the box.

The end flaps 24 and 26 are longer, or extend outwardly farther, than flaps 20 and 22. A scoring 40 is made in flap 24 parallel to scoring 23 and substantially continuous with the outer edges of hinges 27 and 28 and forms a second flap 41 on flap 24, the outer edge 42 of which is serrated. Flap 43 with serrated edge 44 is similarly formed on flap 26. At opposite ends of bottom 46 small elevations 45 are formed in the material at a suitable distance inwardly from the ends of said bottom.

The blank being formed as above described, end flaps 24 and 26 are turned over on the bottom 46, the flaps 41 and 43 being carried with them, as shown in Fig. 2. The hinges being connected to flaps 24 and 26 are now disposed on side flaps 16 and 18 and their portions 36 and 39 are secured to said side flaps by suitable means, such as wire staples. The hinges tend to draw the side and end flaps of the body of the box upwardly and inwardly. Flaps 41 and 43 bend on scorings 40 and 40' respectively as the end flaps move upwardly under the influence of the wings and their outer ends rest upon bottom 46. Hence, after the hinges are secured to the side flaps, the end flaps are inclined upwardly and inwardly and the extension flaps 41 and 43 incline upwardly and outwardly, thus forming a crest in the end closures for ready gripping by the hands to set up the body of the box.

For packing and shipping the boxes, the cover is turned over on scoring 14 onto the bottom as shown in outline in Fig. 2. To set up a box for use the operator turns back the cover as shown in Fig. 3, then grasps

the two crests, one in each hand, and draws flaps 41 and 43 along bottom 46 toward the end flaps, and at the same time elevating end flaps 24 and 26 to vertical position. The 5 flaps 41 and 43 are moved until their lower portions pass behind elevations 45 and abut the lower portions of the end flaps, but since in this position they are higher than the end flaps they must bend or bow toward each other in order that their lower edges shall abut the end flaps. The elevations or guards 45 and the frictional engagement of the serrated edges of the flaps 41 and 43 upon bottom 46 lock the end flaps in upright position, the hinges being substantially closed 10 and drawing the sides of the body into substantial upright position. In reality, each end flap folds upon itself and the portion folded over frictionally engages the bottom 15 of the body of the box and locks the said end in upright position. After the articles are inserted in the body of the box, upon the box being set up as shown in Fig. 4, the cover is turned over on scoring 14 and flaps 20 25 12, 20 and 22 are turned down on the exterior of the sides and ends of the body and a string 47 is wrapped around the box and tied and the package is then ready for delivery.

30 Instead of serrating the edges of flaps 41 and 43 I may cut out the end flaps with material extending beyond flaps 41 and 43 and score the same at points corresponding to the serrated edges, thus providing an additional flap 48 shown in Fig. 8 which bears on bottom 46' of the body of the box and frictionally engages the same when flap 41' is moved against end flap 24'. This frictional engagement of flaps 48 and 41' with bottom 46' locks the end flap 24' in upright position.

In both constructions of frictional means the corners of the box when closed are reinforced by the several thicknesses of material 45 locked in upright position as above described. The box is most rapidly set up and when knocked down occupies a minimum of space.

What I claim is:

50 1. A folding box comprising a bottom section and a cover section, the bottom section having two side flaps and two end flaps each foldable on the bottom section, each end flap being hinged at its opposite ends 55 to the side flaps and the hinges tending to draw all said flaps upwardly and inwardly relatively to the bottom section and each

end flap being of width sufficient to be folded upon itself and to frictionally engage and brace against the bottom section for locking the said end flaps and side flaps in substantial upright position relatively to the bottom section. 60

2. A folding box having integral cover and body portions, the body portions comprising a bottom section, two side flaps and two end flaps each foldable on the bottom section, and wings on the end flaps hinged to the side flaps and tending to draw all said flaps inwardly; the cover being integral 65 with one of the side flaps and foldable thereon, and each of the end flaps being of width sufficient to fold upon itself with its free outer edge in bracing frictional engagement with the said bottom for securing the end 70 flap in upright position relatively to the bottom. 75

3. A folding box made from a single sheet of paper like material and including a bottom, side portions and end portions said 80 side portions and end portions being defined from the bottom by crease lines, said end portions being substantially double the width of the side portions and having their outer halves defined from their inner halves 85 by crease lines, said outer halves being foldable inward against the inner halves with their outer edges engaging the bottom in bracing relation, and means connecting the ends and sides and arranged to draw the 90 latter upward as the former are raised.

4. A folding box made from a single sheet of paper like material and including a bottom, side portions and end portions said 95 side portions and end portions being defined from the bottom by crease lines, said end portions being substantially double the width of the side portions and having their outer halves defined from their inner halves 100 by crease lines, said outer halves being foldable inward against the inner halves with their outer edges engaging the bottom in bracing relation, means connecting the ends and sides and arranged to draw the latter 105 upward as the former are raised, and other means on the bottom of the box arranged to positively engage the outer edges of the ends and hold the outer halves of the ends releasable in bracing position.

In witness whereof I have hereunto subscribed my name this 11th day of April, 110 1921.

CHARLES C. MILLER.
